UNITED STATES PATENT OFFICE.

GEORGE A. STACKHOUSE, OF OAKLAND, CALIFORNIA, ASSIGNOR OF ONE-HALF TO
CHARLES W. PECK, OF SAN LEANDRO, CALIFORNIA.

OVEN-DOOR SPRING CONTROL.

Application filed July 6, 1925. Serial No. 41,646.

This invention relates to an oven door spring control and the method of attaching same, and refers more particularly to the type of oven door that is hinged at the bottom and requires a spring or springs to balance the weight of the door and to keep the door closed.

The oven doors of this type are now usually equipped with compression springs and attached rods and sockets, and have no adjustable features to compensate for the weakening of the compression spring due to heat and wear, and consequently the doors will not stay closed after the springs have weakened.

In my invention I use tension springs which have a longer life than compression springs and the construction and means of adjustment are very simple.

My invention will be more readily understood from the following specifications and drawings, of which—

Figure 1 is a section through an ordinary gas stove oven, showing the oven door open and the broiler door closed.

Figure 2 is a partial elevation of the oven with part of the door frame in section to show the spring and attachments.

Figure 3 is a view of the adjustable link.

Figure 4 is a view of the tension spring.

Figure 5 is a view of another type of spring and link attachment.

Referring to Figure 1, numeral 1 indicates an ordinary gas stove oven with the door 2 provided with hinge member 3 which passes through slot 4 of the door frame 5. Referring to Figure 3, an adjustable link 10 is made of stiff steel wire members 11 and 12, left and right hand threaded at 13 and 14 to engage similar threads in sleeve 15 to form a turnbuckle for longitudinal adjustment of said link. Upper link member 11 is bent at right angles to form the prong or arm 16 and likewise the lower member 12 is bent at right angles to form the prong or arm 17, and said arms are slightly bent as at 18 to prevent them from becoming disengaged from spring and hinge. Lower arm 17 of link 10 pivotally engages the hinge 3 at 20 and the upper arm 16 engages the upper end of an extension spring 21. The lower end of spring 21 is secured to the oven frame by bolt 22.

Referring to Figure 5, a modified form 55 of adjustable link is shown. The tension

spring 30 is tapered at its upper end as at 31 to receive a cone 32, said cone being threaded to receive the upper threaded portion of link 33 which passes through spring 30. The lower end of link 33 is bent at right angles to form the prong or arm 34. Longitudinal adjustment is made by screwing the link 33 in or out of cone 31.

The broiler door 2' is provided with hinge 3', link 10', spring 21' and bolt 22' and is shown in a closed position. In this position the spring 21' is so adjusted that enough pressure bears down on hinge 3' through link 10' to keep the door in an upright or closed position, with the spring and link vertical. As the door is opened the link travels upward and extends the spring until the hinge, in its arc of travel, has reached its horizontal position, which is at a point just before the door is fully opened, then the link 75 and spring take a position at an angle inward from the vertical as shown at 35. This gives an angular thrust on the hinge 3 which is not as effective as a vertical thrust and the door will stay open. As soon as the door is slightly closed, the link and spring will assume a vertical position and the door will then close by the action of the spring.

The opposite end of the doors are provided with the spring and hinge assembly 85 as above described.

From the disclosure it is apparent that I have provided a simple and efficient means for spring controls on oven doors.

While I have described the preferred form of my invention, I wish it understood that any changes may be made in form and construction and arrangement of parts as will not depart from the spirit of the invention.

What I claim is:

In a stove, a frame forming a door opening having a rounded lower frame element, a door having hinge elements extending therefrom adapted to ride on the frame element so as to allow the door to be swung from open to closed position and a spring-depressed rod bearing on the end of each hinge element and opposing the opening of the door, the hinge elements being of sufficient length to increase their distance from the door frame when the door is opened whereby the purchase of the spring-depressed rod is increased.

In testimony whereof I affix my signature.

GEORGE A. STACKHOUSE.
